UNITED STATES PATENT OFFICE.

ALLEN B. WALLACE, OF NEWCASTLE, PENNSYLVANIA.

LOCK.

SPECIFICATION forming part of Letters Patent No. 705,495, dated July 22, 1902.

Application filed January 31, 1902. Serial No. 91,984. (No model.)

To all whom it may concern:

Be it known that I, ALLEN B. WALLACE, a citizen of the United States of America, residing at Newcastle, in the county of Lawrence 5 and State of Pennsylvania, have invented certain new and useful Improvements in Locks, of which the following is a specification, reference being had therein to the accompanying drawings.

10 My invention relates to certain new and useful improvements in locks, and has for its object, primarily, a lock which has economic features of construction and simplicity of operation; furthermore, a lock in which the lock-bolt may be secured from the interior of the door against movement when a key is inserted to actuate the same.

With the above and other objects in view the invention further consists in the novel details of construction and combination of parts 20 to be clearly described in the following specification and fully set forth in the claims.

Referring to the accompanying drawings, in which like characters of reference indicate 25 similar parts throughout the several views, Figure 1 is a plan view of a lock containing my invention with the plate removed. Fig. 2 is a plan view, partly broken away, showing the guide secured to the inner face of the casing-plate. Fig. 3 is a plan view of the 30 latch member. Fig. 4 is an underneath plan view of the lock-bolt. Fig. 5 is a sectional view of the casing, showing the engaging member for actuating the lock-bolt. Fig. 6 is a like view showing the pawl for securing the lock-bolt; and Fig. 7 is a plan view, partly in section, showing the key for operating the lock.

The latch 1 carries a contracted shank 2 40 and has the usual opening 3 therein, in which engages the arm, suitably mounted on the knob-shank. (Not shown.) Stops 27 are carried by latch 1 and limit the forward movement of the same by engagement with lugs 7 and 8. A downwardly-extending projection 4 is secured to the inner face of the plate 5 of the lock-casing and has an aperture therein through which the contracted shank 2 of the latch-bolt operates. A spring 6 is mounted 45 on the shank 2 and engages the one side of

projection 4 and the end of the latch-bolt 1. The forward end of the latch-bolt operates through lugs 7 and 8, the former receiving one of the screws for securing the outer plate to the casing.

55 Between the U-shaped guide 9, carried by the casing-plate 5, operates a pin 10, rigidly secured to the rear end of the lock-bolt 11 in a manner as will permit the lock-bolt to have a pivotal as well as a longitudinal movement. 60 The forward end of the lock-bolt is suitably recessed, as shown at 12 and 13, for the reception of the lug 14, which is extended and enlarged and serves as a means for securing one of the plate-screws. (Not shown.) The 65 lock-bolt is cut away, as at 15, in order to permit of the same passing the lug 14 without engagement. The numeral 16 designates a similar lug secured in the door-frame member 17, adapted to engage in recess 13 when the 70 lock-bolt is in its locked position.

An arc-shaped cut-away portion 18 is formed in the lock-bolt and engages the arm 19, which is mounted on a shank 20, pivotally secured in the casing. The shank is operated by a suitable key and is shown as having square ends. The lower portion of projection 4 is enlarged and has one end of a flat spring 21 rigidly secured therein, the forward portion of which spring is bent downwardly 80 and engages the upper face of the lock-bolt. The free end of this flat spring is bent upwardly to form a lug 22, the purpose of which will be hereinafter stated. An arm 23 is pivotally secured in the casing and has the ends 85 of its shank notched for the purpose of receiving a key in order to operate the arm. The arm is mounted above the spring and is adapted to have its free end engaging the latter when in a vertical position. Thus when 90 it is desired to prevent operation of the lock-bolt when the latter is in a locked position or otherwise it is only necessary to move the arm downwardly, when the same will engage the spring and have its movement limited by the 95 lug 22, previously mentioned. For the purpose of securing the arm in an inoperative position a leaf-spring 24 is secured in a boss 25, whereby the free end of the arm may be supported by the spring and disengaged there- 100

from by slight downward pressure of the key when the latter engages in the shank of the arm.

A stop 26, secured in the casing, prevents 5 undue upward movement of the arm.

It will be noted that the flat spring exerts pressure at all times upon the lock-bolt, thus securing the same normally in engagement with the lugs, which are received in the recesses 12 and 13, and when in a locked position the lock-bolt recesses are each engaged, the former by lug 14 and the latter by lug 16.

I desire to call particular attention to the fact that with a lock constructed as above described 15 it will be absolutely impossible to use a "jemmy," as the arm 23 is free to drop of its own weight, so that the person opening the lock must be provided with both keys, it being required that the arm 23 be held up by 20 its key in order that the arm 19 may be operated to actuate the bolt. As shown, the arms are preferably operative from both sides of the lock.

Having thus fully described my invention, 25 what I claim as new, and desire to secure by Letters Patent, is—

1. The combination with the lock-casing having a projection therein through which operates the spring-pressed latch, of a lock-bolt 30 secured in the casing and carrying a pin, a guide in which the pin operates, the under face of the front end of the lock-bolt having recesses formed therein, a lug secured in the

casing and normally engaging in one of said recesses, the lower end of the said projection 35 having a flat spring rigidly secured therein, the free end of the spring extending downwardly and engaging the upper face of the lock-bolt, with a lug carried by the said end, means pivotally secured in the casing for engagement with said spring, whereby the lock-bolt is held in an inoperative position, and means for operating the lock-bolt, substantially as described.

2. The combination with the lock-casing 45 having the latch-bolt therein, of a lock-bolt mounted so as to have a pivotal and longitudinal movement, means for operating the lock-bolt, the free end of said lock-bolt having recesses therein, a lug secured in the casing and engaging in said recesses, a spring having its one end rigidly secured in the casing and its free end engaging the upper face of the lock-bolt, means in the casing for engaging said spring whereby movement of the 50 lock-bolt is prevented, means for supporting said means, and means for limiting the movement of said first-named means, substantially as described.

In testimony whereof I affix my signature 55 in the presence of two witnesses.

ALLEN B. WALLACE.
